APPARATUS FOR GRINDING ARCUATE OR
ANNULAR WORK

Henry E. Caston, Akron, Ohio

Application July 31, 1947, Serial No. 764,944

10 Claims. (Cl. 51—105)

1

This invention relates particularly to apparatus for grinding or cutting arcuate or annular work.

Heretofore arcuate work, such as segmental steel rings used in automotive rim forming machines, has been reconditioned by annealing the same, cutting the worn forming surfaces thereof on a boring mill or other machine, and rehardening the reconditioned work. This procedure, however, was not only very expensive but was unsatisfactory because rehardening of the work caused it to become warped.

One object of the present invention is to provide improved apparatus for reworking or resurfacing such annular or arcuate work, which makes possible the elimination of annealing and rehardening operations, with consequent elimination of warping of the work which would materially affect the accuracy thereof, and with a substantial reduction in the cost of reworking procedure.

Another object of the invention is to provide apparatus of the character described, including improved work-supporting means which is readily adjustable to support annular work of varying sizes and shapes.

Another object of the invention is to provide apparatus of the character described having improved means for accurately orienting the work for reworking operations thereon.

These and other objects of the invention will be manifest from the following brief description and the accompanying drawings.

Of the accompanying drawings:

Figure 1 is a side elevational view of grinding apparatus embodying the features of the invention in association with an adjustably mounted rotary grinding tool.

Figure 2 is a view of the improved work-supporting mechanism with the work in place therein for a grinding operation, as viewed on the line 2—2 of Figure 1.

Figure 3 is an enlarged fragmentary view of the work-supporting mechanism, as viewed in Figure 2, but with the work shown therein by chain-dotted lines.

Figure 4 is a cross-section taken on the line 4—4 of Figure 3.

Figure 5 is a fragmentary view similar to Figure 3, illustrating a modified form of the invention.

Figure 6 is a perspective view of the apparatus of Figure 1, but illustrating in greater detail the adjustable mounting means for the rotary grinding wheel.

Referring particularly to Figures 1 to 4, and 6 of the drawings, the numeral 10 designates a

2

steel ring composed of a series of arcuate segments 11, 11 (see Figure 2), the inner periphery of the ring conforming to a certain rim contour and the outer periphery being of predetermined diameter for mounting in a rim-forming machine of known type (not shown). The present invention provides a means for effectively refinishing said rim contour of the ring. To this end, the separate ring segments 11 are radially adjustably mounted, in ring-like arrangement by means of work-supporting devices 13, 13, one for each segment, upon a backing plate 14 which is fixed on a free end of a shaft 15, rotatably mounted on a support 16 and driven by suitable power means 21 through belting 17. A grinding wheel is rotatably mounted on a universally adjustable support S, of known type, to extend freely toward work so mounted on the backing plate, and to be presented in substantially any desired angle or position with respect to the work (see Figure 4). In Figure 6 there is illustrated a suitable universally adjustable mounting means M for support S, the adjustments being accomplished as by operation of hand wheels H and R.

As best illustrated in Figures 2, 3, 4 and 6, each work-supporting device 13 may include a bracket 18 having a web portion 19 on a radius approximating generally the maximum radius of backing plate 14, and a right-angled wall 20 at the inner edge portion of the web provides radially inwardly and outwardly extending flanges 23 and 24, respectively, for flat engagement with the outer face of the backing plate, clamping bolts 25 and 26 being provided through said flanges and through one of a series of circumferentially spaced radial slots 27, 27 in said plate. A guide rib 28 on the inner face of wall 20 is slidable in its slot 27 for maintaining desired angularity of the bracket in all radially adjusted positions thereof.

Each work segment 11 is mounted on its re-

spective bracket 18 by clamping it between spaced

spacer blocks 29, 29 secured to the inner flange

23 of the bracket by means of "Allen Head"

screws 30, and a clamping lug 31 having a screw

32 slidably received through a bore, 33 therein

and adjustably threaded into the outer edge of

web 19 of the bracket.

The outer periphery of each ring segment 11

has a given radius which may be utilized for

orienting the segment with respect to the others

for grinding operations. To this end, three cir-

cumferentially and laterally spaced threaded pins

34, 35 and 36 may be adjusted through corre-

spondingly threaded apertures in web 19 of the

bracket, to extend radially inwardly thereof a substantial distance, and nuts 37 are provided on radially outwardly projecting ends of the pins for locking the same in adjusted position. The pins are of metal of a character which permits the inner ends thereof to be ground to a predetermined radius from the center of backing plate 14, in a manner to be described later, for accurate orienting engagement with said outer periphery of the segment.

In the use or operation of the improved apparatus for grinding a segmental ring 10 of given size, such as the size best shown in Figures 1, 2 and 4, the brackets 18, through the bolts 25 and 26, are radially adjusted along the slots to circumferentially spaced positions in which the inner ends of the three triangularly arranged or staggered pins 34, 35 and 36, of the respective brackets, are at a radius from the center of backing plate 14 slightly less than the true radius of the outer periphery of the ring 10, or in other words of the segments 11. With the segments clamped in this relation, as best shown in Figure 3, the operator through adjustment of hand wheels H and R (Figure 6), may present the rotary grinding wheel W, while rotating at suitable speed, at the desired position and angle to grind the inwardly presented ends of the pins to an accurately predetermined radius the same as the given radius of the outer peripheral surfaces of the ring segments 11.

With the pins thus accurately radiused at the inner ends, the operator next mounts a segment 11 in each bracket 20, holding the outer peripheral surface thereof self-centeringly against the ends of the pins, and then firmly clamps the segment between the spacer blocks 29, 29, and the clamping lug 31, by tightening the screw 32. A separate spacer block 38, may be clamping engaged between an outwardly extending portion 31a of the lug 31 and the outer flange 24 to enhance said clamping action on the segment 11. When all of the segments are similarly clamped in accurately centered relation, the operator may move rotary grinding wheel W to various angularly adjusted positions to grind the various inner surface portions of the segments, as shown in Figure 4, for example. The work may in this manner be accurately resurfaced to predetermined contour, as checked from time-to-time 50 with a contour template.

The apparatus may be similarly operated and used for regrinding either segmental or continuous rings of various sizes and proportions, by radially adjusting the brackets 18 and grinding the ends of pins 34, 35 and 36 accordingly in each instance. If necessary, the metal spacer blocks 29 may be ground by use of wheel W to adjust the work to suit the clamping lugs 31. In any case the segments 11 should project beyond the outer edges of the brackets thereof to be properly engaged by the clamping lugs.

Referring now to Figure 5, there is shown work-supporting and grinding apparatus, which is in all respects like that previously described except that it is designed for grinding the outside surfaces of annular or arcuate work, such as segments 40 of a segmental ring 41. Each segment is oriented or centered against pre-ground, arcuate ends of three pins 43, 44 and 45 in each of a series of brackets 46, radially adjustably mounted on a rotatable backing plate 42, as before, the ends of the pins, however, being presented outwardly and engaging inner peripheral portions of the segment. Clamping lugs 47, cor-

responding to lugs 31, are operable by means of screws 48 to hold the work in position on the bracket 46 and against the backing plate.

Other modifications of the invention may be resorted to without departing from the spirit thereof or the scope of the appended claims.

What is claimed is:

1. In apparatus for treating arcuate or annular work, the combination with a cutter or other treating tool adjustably mounted to be presented in various adjusted positions, of a support, a backing member mounted on said support to rotate about an axis and having a work-supporting face portion in a plane transversely of said axis, power means operable to rotate said backing member about its axis, a work-holding bracket, means for mounting said bracket on said backing member against said face portion thereof in different adjusted positions radially of said axis, said bracket having orienting projections extending therefrom radially of said axis for engaging one arcuate side of the work, an adjustable clamping device of said bracket for clamping the work against said face portion of the backing member while said arcuate side of the work is oriented against said projections, thereby to present the opposite arcuate side of the work for treating engagement by said tool as said member is rotated.
2. The combination as set forth in claim 1, said orienting projections comprising elements radially adjustable to fixed positions with respect to said brackets presenting free ends of the elements at radii corresponding to radii of said opposite arcuate side of the work.
3. The combination as set forth in claim 2, said free ends of said elements being of material which can be reduced by said tool to accurately predetermined radii complemental to the radii of the first-named arcuate side of the work.
4. In apparatus for treating arcuate or annular work, the combination with a cutter or other treating tool adjustably mounted to be presented in various adjusted positions, of a support, a backing member mounted to rotate about an axis and having a work-supporting face portion in a plane transversely of said axis, power means operable to rotate said backing member about its axis, a plurality of work-holding brackets, adjustable means for mounting said brackets on said backing member against said face portion thereof in different adjusted positions radially of said axis, said brackets each having a plurality of orienting projections extending therefrom radially of said axis for engaging an arcuate side of the work, an adjustable clamping device on each said bracket for releasably clamping the work against said face portion of said backing member while said arcuate side of the work is oriented against said projections, thereby to present the first-named arcuate side of the work for treating engagement by said tool as said member is rotated.
5. The combination as set forth in claim 4, said orienting projections comprising elements radially adjustable to fixed positions with respect to said brackets presenting free ends of the elements at radii corresponding to radii of the first-named arcuate side of the work.
6. The combination as set forth in claim 5, said free ends of said elements being of material which can be reduced by said tool to accurately predetermined radii complemental to the radii of the first-named arcuate side of the work.
7. The combination as set forth in claim 6, said

5

adjustable mounting means comprising a radial slot in said member for each said bracket, guide portions on said brackets slidably engageable along said slots, and clamping bolt means through said brackets and said slots.

8. In apparatus for treating arcuate an annular work, the combination with a cutter or other treating tool adjustably mounted to be presented in various adjusted positions, of a support, a backing member mounted on said support to rotate about an axis and having a work-supporting face portion in a plane transversely of said axis, power means operable to rotate said backing member about its axis, a plurality of work-holding brackets, adjustable means for mounting said brackets on said backing member against said work-supporting face portion thereof in different adjusted positions radially of said axis, said brackets each having at least three transversely and circumferentially spaced orienting projections extending therefrom radially of said axis for engaging an arcuate side of the work, an adjustable clamping device on each said bracket for releasably clamping the work against said face portion of said backing member while said arcuate side of the work is oriented against said projections, thereby to present the first-named arcuate side of the work for treating engagement by said tool as said member is rotated.

9. The combination as set forth in claim 8, said free ends of said projections being of material which can be reduced by said tool to accurately predetermined radii complementary to the radii of the first-named arcuate side of the work.

10. In apparatus for treating arcuate or annular work, the combination with a cutter or other

6

treating tool adjustably mounted to be presented in various adjusted positions, of a support, a backing member mounted on said support to rotate about an axis and having a work-supporting face portion in a plane transversely of said axis, power means operable to rotate said backing member about its axis, a plurality of work-holding brackets, adjustable means for mounting said brackets on said backing member against said work-supporting face portion thereof in different adjusted positions radially of said axis, said brackets each having a plurality of orienting projections extending inwardly radially of said axis for engaging an arcuate side of the work, an adjustable clamping device on each said bracket for releasably clamping the work against said face portion of said backing member while said arcuate side of the work is oriented against said projections, thereby to present the first-named arcuate side of the work for treating engagement by said tool as said member is rotated.
